UNITED STATES PATENT OFFICE.

FRANK E. YOUNG, OF BROOKLYN, NEW YORK.

STEEL BARREL.

No. 891,895.

Specification of Letters Patent.

Patented June 30, 1908.

Application filed April 27, 1907. Serial No. 370,543.

To all whom it may concern:

Be it known that I, FRANK E. YOUNG, a citizen of the United States, residing in Brooklyn, in the county of Kings and State of New York, have invented certain new and useful Improvements in Steel Barrels, of which the following is a specification.

This invention relates to metal or steel barrels or similar receptacles in which the heads, formed separately from the body, are secured to the latter in such manner that a fluid-tight receptacle is provided, this being accomplished in an improved manner by means of a malleable iron clamping ring.

15 In the drawings accompanying and forming part of this specification, Figure 1 is a side view partly in section and with a part thereof broken away, illustrating one of these improved metal or steel barrels; Fig. 2 is an enlarged cross-sectional view of one end of the barrel with its head united to the body; Figs. 3 to 8 illustrate the mode of attaching the head to the body, Figs. 3 and 4 illustrating the body, Figs. 5 and 6 the body and the head, and Figs. 7 and 8 the body, head and clamping ring, Fig. 2 being a successive view to said Fig. 8.

The present construction is an improvement upon the prior art of which I am aware, in that it does not require the formation of a recess in the side wall of the clamping ring for the purpose of forming a shoulder, which cannot ordinarily be of very great depth without materially increasing the thickness 35 of the ring, which is undesirable, and which recess moreover does not permit of the folding of one member, the head or body, around the folded metal of the other member, so as to more completely and effectively interlock 40 these two members one with the other independently of the clamping ring. By bending a part of one member, as the body, upon itself, and then bending a part of the other member, as the head, around it not only is an 45 increased clamping surface or shoulder formed on the receptacle itself for the engagement of the clamping flange of the malleable iron ring, but an effective locking of the parts is obtained when the ring is in position, while 50 that which permits this also reinforces the edge of the barrel. This effective locking is not the case in those structures where one member is merely bent over an unbent portion of the other member, since in such structures there is no positive locking of the parts, the inseparability of the members depending

entirely upon the pressure with which the parts are clamped together between opposed surfaces and the use of solder, so that as a matter of fact such structures are but a form of slip-joint connection, and under great pressure one part can slip or pull away from the other, whereas in the present case there is in addition to the clamping pressure which holds the parts together a distinct locking of those parts by a flange which underlaps both the folded portions of the barrel and head, so that in order to separate the head from the body the flange of the clamping ring would have to be actually broken off.

The present improvement comprises a body or barrel portion 2 and a flanged head 3 of any desired shape, the flange 4 of which extends toward the ends of the barrel. The body 2 has its outer edges 5 each first bent 75 upon itself once or a plurality of times, preferably the latter, to form a bead or shoulder 6 which also materially reinforces and strengthens the edge portion of the barrel. The flanged head is then inserted and its free 80 edge 7 bent over this bead to the desired extent, preferably so that its edge will be in proximity to the exposed edge of the body bead. A clamping ring 8, usually of malleable metal is then located in position. In 85 the present instance it is inserted into the end of the barrel so as to overlap the flange of the head and hold the same tightly in engagement with the barrel body as at 9. This clamping ring is provided with a bendable locking 90 flange 10, which is then by pressure, usually by rolling, forced around the folded or bent portions of the head and body so as to underlap the same, thereby completely encircling 95 and enfolding the same in the manner shown in Fig. 2, thereby positively locking the parts together in such a manner that it is not possible to separate the head from the body except by breaking or shearing the flange.

In the foregoing construction there is a 100 positive clamping of one member, as the head, to the other member, as the body, without depending upon the formation of a recess to form a shoulder in the wall of the clamping member or ring, not merely by two 105 opposed clamping surfaces, but by means of a flange which positively engages and overlaps a shoulder formed by bending the metal of both the body and the head one within the other which also reinforces the edge of the 110 barrel. The clamping ring is so formed that preferably a part thereof will project beyond

the locking flange and form a foot or rest for the barrel.

By constructing the barrel in the manner described the parts are so effectively locked together, as a section cut therefrom discloses, that to all intents and purposes they are the same as welded together, and this effective fluid tight connection is obtained without the use of solder or other holding means.

10 As hereinbefore stated, one of the parts may be bent upon itself once or a plurality of times so that when the metal of the other part is bent therearound four or more thicknesses of metal will be the result. In the 15 present embodiment it will be observed that the body and closure flange are bent to form five thicknesses of metal, which thus provides a relatively enlarged shoulder made up of three thicknesses of metal, while the free 20 end of the locking flange of the clamping ring is bent at an abrupt angle to such flange and inwardly, as shown in the drawing, and thus overlaps the shoulder in an effective manner 25 positively to lock the bent portions of the body and closure flange within the walls of the ring, thereby to form a fluid-tight joint.

I claim as my invention:

1. A barrel or receptacle comprising a body and a head united by a fluid tight, 30 solderless joint, said body and head being bent one upon the other to form at least four thicknesses of metal thereby to form a shoulder made up of at least two thicknesses of metal, and an annular malleable clamping 35 ring having a bendable locking flange overlapping said bent portions with its free end bent at an abrupt angle to such flange so as to

overlap **said shoulder** thereby positively to lock said bent portions within the walls of said ring.

2. A barrel or receptacle comprising a body and a flanged head united by a fluid tight, solderless joint, said flange and head being bent one upon itself a plurality of times and the outer upon such bent portions 45 to form five thicknesses of metal and thereby forming a shoulder made up of three thicknesses of metal, and an annular malleable metal clamping ring having a bendable locking flange with its free end bent at an abrupt 50 angle to such flange so as to overlap such shoulder thereby positively to lock said bent portions within the walls of said ring.

3. A barrel or receptacle comprising a body and a flanged head united by a fluid 55 tight, solderless joint, said body having a part bent upon itself and said flange being bent around such bent portion of the body and forming therewith a shoulder located exteriorly of the barrel, and a malleable metal 60 clamping ring having a part thereof located interiorly of and in parallelism with the flanged head, and a bendable locking flange located exteriorly of and in parallelism with the bent portions of such head and body with 65 its free end bent inwardly at an abrupt angle to such flange so as to overlap such shoulder thereby positively to lock said bent portions and body within the walls of said clamping ring.
